UNITED STATES PATENT OFFICE.

EDWIN S. MIX, OF ROCHESTER, NEW YORK, ASSIGNOR TO HICKOK MANUFACTURING COMPANY, OF ROCHESTER, NEW YORK, A CORPORATION OF NEW YORK.

BELT BUCKLE.

Application filed March 30, 1922. Serial No. 548,163.

To all whom it may concern:

Be it known that I, EDWIN S. MIX, a citizen of the United States, and resident of Rochester, in the county of Monroe and State of New York, have invented certain new and useful Improvements in Belt Buckles, of which the following is a specification.

The present invention relates to belt buckles and more particularly to the type in which a frame is provided with a front plate, the rear face of which serves as a clamping surface for one end of a belt, the other end of the belt being anchored on a clamping member which is pivotally mounted on the buckle frame and has a clamping surface arranged to cooperate with the rear face of the front plate to hold the first mentioned belt end against movement. An object of this invention is to provide an improved clamping surface for the clamping member, so constructed as not to injure the belt, while at the same time adapting itself to the thickness of the belt.

To these and other ends, the invention consists of certain parts and combinations of parts, all of which will be hereinafter described: the novel features being pointed out in the appended claim.

In the drawings:

Fig. 1 is a face view of a belt buckle with the belt ends connected thereto;

Fig. 2 is a side view;

Fig. 3 is an enlarged vertical section through the belt buckle;

Fig. 4 is a detail sectional view with the clamping member removed;

Fig. 5 is a view of one end of the buckle frame;

Fig. 6 is a detail sectional view showing the clamping member in clamping position;

Fig. 7 is a detail view of the clamping member; and

Fig. 8 is a rear view of the buckle.

Referring more particularly to the embodiment of the invention herein illustrated, 1 indicates the front plate which is curved longitudinally and transversely and has side flanges 2 projecting from opposite edges thereof. These side flanges, in this instance, 50 have inwardly turned flanges 3 and on these inwardly turned flanges, the clamping member is arranged.

The clamping member, in this instance, embodies a pivoted piece having a loop 4 rigid therewith around which an end 5 of

the belt is passed. At the inner side of this loop a transverse opening is provided through which a pivot pin 6 extends, the pivot pin being shorter than the width of the loop so that its ends lie within the lines 60 of the ends of such loop. This pivot pin 6 is pivoted to the flanges 3 preferably by extending the ends of said flanges 3 beyond the side flanges 2 and rolling said extensions to provide bearing loops 7. The clamping member adjacent said pivot pin is provided with a groove extending, in this instance, parallel with said pivot and in this groove a strip 8 of yielding material is secured, the edges of the walls of the groove being bent 70 inwardly at 9 into binding engagement with the yielding strip 8 so that the strip is firmly held in the groove under compression. The strip projects beyond the groove and provides the clamping surface for clamping the 75 belt end 11 against the rear face of the front plate 1. In this instance, this yielding material is in the form of leather and when it engages the belt end 11, it is deflected laterally and compressed thus adapting itself 80 to the thickness of the belt and, furthermore, as it is of soft material, it does not mar the rear face of the belt end. The laterally deflected portion tends to straighten out when tension is placed on the belt and 85 this straightening action will be proportional to the thickness of the belt, increasing with a thin belt. Heretofore, this binding action has been established most generally by a metallic surface which will not accommodate itself to the thickness of the material and, furthermore, will cut or mar the rear face of the belt. Furthermore the leather clamping surface acting on the leather belt gives a very desirable friction which 90 prevents slipping of the belt.

From the foregoing it will be seen that there has been provided in a belt buckle of the type described a clamping member with a clamping surface so formed as to adapt 100 itself to belts of different thicknesses and which will not mar the belt.

What I claim as my invention and desire to secure by Letters Patent is:

A belt buckle comprising a front plate 105 having a rear face thereof serving as a clamping surface, a clamping member pivotally mounted in rear of the front plate and provided with a belt anchoring member for one end of the belt and formed with a 110

groove extending longitudinally of the pivot of the clamping member, and a strap of leather mounted in the groove projecting beyond the latter and having the opposite 5 walls of the groove deflected inwardly into binding engagement with opposite sides, the projecting portion being adapted to be de-

flected laterally by the belt as the clamping member is moved to clamping position and tend to straighten by the tension on the belt 10 in order to accommodate itself to the thickness of the belt.

EDWIN S. MIX.
